(57) **CLAIM**

The ornamental design for an electronic indicator device for cleaning monitoring, as shown and described.

DESCRIPTION

FIG. 1 is a perspective view of a new design for an electronic indicator device for cleaning monitoring;

FIG. 2 is a right side view thereof; and the left side view being a mirror image thereof;

FIG. 3 is a front plan view thereof;

FIG. 4 is a top plan view thereof;

FIG. 5 is a rear view thereof; and,

FIG. 6 is a bottom view thereof.

The broken lines in the drawings illustrate portions of the electronic indicator device for cleaning monitoring which form no part of the claimed design.
